United States Patent Office.

MASON M. MILES, OF AURORA, ILLINOIS.

Letters Patent No. 73,913, dated January 28, 1868.

IMPROVEMENT IN VAPOR-INHALERS.

The Schedule referred to in these Letters Patent and making part of the same.

TO ALL WHOM IT MAY CONCERN:

Be it known that I, MASON M. MILES, of Aurora, in the county of Kane, and in the State of Illinois, have invented certain new and useful Improvements in Catarrhal Instrument and Medicated Vapor-Inhaler; and do hereby declare that the following is a full, clear, and exact description thereof, reference being had to the accompanying drawings, and the letters of reference marked thereon, making a part of this specification.

A represents a jar or vessel, constructed of glass or other suitable material. B represents an elastic rubber bulb or globe, supplied with a valve, *a*, at its top, for the admission of atmospheric air or vapor. E represents an adjustable neck or stopper to vessel A. C represents a tube or pipe, running from the bulb B, through the neck E, into the vessel A. *x* represents an opening in neck E. D represents an adjustable flexible tube, provided with a perforated nozzle, G, and attached to the neck E at *x*. H also represents an adjustable non-elastic or rigid tube, attached in the same manner, and to be used instead of flexible tube D, as may be desired.

These tubes may be made of any given dimensions, and of any suitable material. The vessel A may be partially or entirely filled with any given liquid mixture or medicine.

By pressing on the globe B, the air is forced through the pipe C into and through the medicine in the vessel A, thereby producing a medicated vapor, and that thence through the opening *x* and tube D or H into the throat, lungs, head, rectum, or wherever desired. In case gases are to be used, an additional check-valve may be placed in the neck E.

Having thus fully described my invention, what I claim as new, and desire to secure by Letters Patent, is—

The combination of the tubes C D with the vessel A and bulb B, the various parts being constructed substantially as and for the purposes specified.

In testimony that I claim the foregoing, I have hereunto set my hand, this 22d day of November, 1867.

M. M. MILES.
